ORS OF SEVEN-EIGHTHS TO GEORGE D. HASKELL, OF BOSTON, MASSACHUSETTS.

PROCESS OF MAKING COKE.

1,191,943.

Specification of Letters Patent. Patented July 25, 1916.

Application filed November 7, 1914. Serial No. 870,809.

To all whom it may concern:

Be it known that we, HENRY W. BUHLER and CHARLES J. EMERSON, citizens of the United States of America, residing at Boston, county of Suffolk, State of Massachusetts, have invented certain new and useful Improvements in Processes of Making Coke, of which the following is a specification.

This invention relates to certain improvements on the old and well known process of making coke in what are known as "wasting" ovens, of which the so-called "beehive" oven is the oldest and best known type. Its purpose and effect is to materially shorten the time consumed in the coking process, to recover the best portion of the by-products, such as tar, ammonia, etc., without requiring the use of any costly arrangement of flues subjected to temperatures so high as to be rapidly destructive thereof, and also to produce a good quality of coke by direct and even application of the heat employed.

In the simple process heretofore generally used with the "wasting" ovens, the coal is placed in an oven having a trunnel opening in the top for escape of gases of combustion, and doors provided with openings for the admission of regulated quantities of air. The coal is spread upon the floor of the oven in an even layer. In usual practice a layer of an initial thickness of about 32 inches is employed. This is lighted from the top, regulated quantities of air are admitted through the doors to support combustion of the gases distilled from the charge, and the gases of combustion escape through the trunnel head. The heat of the oven walls, retained from previous operations, or conducted from adjacent ovens in similar operation, produces this initial distillation and combustion. The direct heat of the gases burning in the oven continues and completes the distillation and coking operation. The products of the distilling process are mainly hydrocarbon gases. The carbonaceous residue of the coal cokes and forms the only useful product realized from the operation, which requires approximately 48 hours for its completion with a charge of the above mentioned thickness. It is evident that as distillation proceeds from the top of the charge downward there will be a thick, nearly gas-tight layer of coke formed over the coal remaining at the bottom of the charge during the latter part of the opera-

tion, which layer of coke will interfere with the transmission of heat to, or liberation of gas from, this bottom layer of the charge. Consequently, the gases least in quantity and poorest in quality are supplied to the combustion zone in the top of the oven, and the least amount of heat generated there, at the very time when the greatest heat is needed to penetrate the overlying coke and complete the distillation in the lowermost stratum of the charge. This is what prolongs the operation to 48 hours or more in this old type of oven. One great advantage of this simple process is the even character of the coke produced. The coking operation being progressive, from the top downward, there are no breaks or planes of demarcation in the grain or formation of the coke.

While the simple type of "wasting" oven above described still occupies the principal field, at least in this country, numerous more elaborate types of ovens have been designed and used for shortening the period of operation and recovering the by-products from the gases of distillation. These ovens have more or less elaborate systems of flues in the walls and under the floors thereof. The gases distilled from the charge are not burned in the oven, in contact with the coal and coke, but are drawn off, as distilled, passed through suitable condensing apparatus which extracts the by-products, and the purified, fixed gases are then led back and burned in the flue system, with admixture of air. The heat so generated must pass through the flue and oven walls, by conduction, before it reaches the charge in the oven. To secure the necessary heat in the oven a much higher temperature must be created in the flues. Hence a costly construction of highly refractory materials is required, and, even with this deterioration is rapid in the standard "by-product" oven, so that repairs, together with interest on large initial cost, creates a large item of expense. Furthermore, the coke produced by such conducted heat is not as good for some purposes as that produced by the directly applied heat of the old wasting process, and is apt to show breaks, or planes of demarcation, where the coking actions starting from opposite sides or surfaces of the charge, meet in the interior thereof, thus destroying the even grain, or homogeneous character of the product.

The present invention combines certain of the features of advantage of both of the above described processes, and avoids their principal disadvantages. A simple oven of 5 the "wasting" type is employed, together with the usual condensers, scrubbers and washers of the common form for treating the gases distilled in the oven during a portion of the operation, to remove the by-products therefrom. The purified gases emerging 10 from the scrubbers, etc., are returned to be burned in an oven, over the charge therein, during the later stage of the coking operation, together with the residual gases 15 distilled from the lower strata of the charge during that final stage. Thus an intense and easily controllable heat is generated during the later stage of the coking operation which greatly shortens the time consumed. 20 This heat is applied directly to the charge, combustion taking place in the oven, over the charge, as in the old wasting process. The coking action is progressive from the top downward, and the same homogeneous 25 product results as in the "wasting" oven. On the other hand, the major portion of the by-products are recovered. There being no combustion in the oven during the first stage the gases distilled pass to the condensing 30 apparatus with all their normal content of tar, ammonia, etc., undisturbed. The richest gases are the most volatile, and these are given off during this preliminary stage. All 35 this is accomplished with the old, cheap and durable form of wasting oven, and the process can be applied to the thousands of such ovens now in use by adding a condensing apparatus, and the necessary piping, with perhaps a blower, and certain re-arrangements 40 of the air inlets.

The simplest form of apparatus for carrying out this improved process involves the use of a single oven and a gasometer in which the gases may be stored until the 45 time for returning them to the oven arrives. In commercial use, however, a series of ovens would be built together, and certain of these would be distilling gases while others were burning them, and vice versa, so that the intermediate storage of gases in any large 50 quantity would not be necessary.

The accompanying four sheets of drawing illustrate one form of apparatus arranged 55 to carry out the improved process or method herein referred to, in the best manner at present known to us.

Figure 1 is a side elevation of an apparatus with parts broken away, showing the 60 general arrangement of a set of two ovens and connections for carrying out our process of coke making. Fig. 2 is a longitudinal cross section of one oven taken on line 2-2 of Fig. 1, but on an enlarged scale. Fig. 3 is a vertical cross section on line 3-3 of Fig. 65 2, showing both ovens, and Fig. 4 is a horizontal

section of one oven on line 4-4 of Fig. 2.

Throughout the drawings like reference characters indicate like parts.

1, and 101, represent two coke ovens of a 70 standard type. In practice a long series of such ovens would be built closely together, to interchange heat by conduction. These ovens are of rectangular horizontal cross section with arched roofs 4, 104, rising to 75 peaks midway of the length of each. At the peaks of the roofs are the usual tunnel heads, one of which is shown at 102, each having a removable cover 103, as shown in Fig. 2. At each end of each oven are doors 80 5, 105, having openings such as 106, (Figs. 2 and 4) through which pass nozzles for air jets 7, 107, and gas jets 23, 123. Similar air nozzles 8, 108, and gas nozzles 24, 124, may be inserted through openings in the oven 85 roofs and side walls.

Each oven has one or more gas outlets. Preferably these are in the roof, as shown at 9, 109, though they might be placed at other points. Each gas outlet is controlled 90 by a valve 10, 110, communicating with hydraulic main 11. This main opens into an exhaust pipe 12, controlled by valve 13, and leading to a series of washers, scrubbers, condensers, etc., 14, 14, of standard 95 type. Some means, such as suction fan 15, for accelerating the movement of the gases, may be inserted in the circuit at a convenient point.

16, is a gasometer into which the purified 100 gases may be led by pipe 17, when valve 18, is open.

19, is an outlet pipe from the gasometer controlled by valve 20. A by-pass, or cut-out pipe, 21, controlled by valve 22, connects 105 pipes 17, and 19, outside of the gasometer. The gas outlet, or return pipe, 19, has a branch 25, communicating with gas nozzles 24, 124, in the oven walls, and another branch 33, to gas nozzles 23, 123, in the oven 110 doors. Each connection to a gas nozzle is controlled by a valve 26, or 126. Any convenient form of damper for controlling the inflow of air by natural draft may be used. We have shown cup-shaped, sliding dampers 115 27, 127, having radial air inlets as shown at 128 (see Figs. 2 and 4).

38, represents a blower or air compressor discharging through pipe 37, to the air nozzles in the doors of the oven, and through 120 pipe 39, to the air nozzles 8, 108, in the walls of the ovens. Each connection to an air nozzle is controlled by a valve 34, or 134.

The improved process which forms the 125 subject of this invention may be carried out with the above described apparatus as follows: Assuming only one oven as 101, to be used, the charge of coking coal is introduced and leveled off in the usual manner and the doors 105, placed in position. The heat of 130

the oven roof and walls carried over from a previous operation would usually be sufficient to start the distillation of gases in quantity from the charge, as soon as the 5 moisture contained in the coal is vaporized. If necessary the further heating of the oven may be accomplished by opening the dampers 127, by pulling them outwardly to admit air through some of the holes 128, which 10 will cause the gases initially distilled to burn, until the desired temperature is secured in the oven. The cover 103 is left off the trunnel head so that the gases of combustion may escape. This necessary pre- 15 heating may also be accomplished wholly or in part by burning some of the gases stored in gasometer 16, in the oven before the charge is introduced. When the distillation is under way in the oven at a rate sufficient to warrant collection of the gases for 20 treatment, the trunnel head cover 103, is placed in position, the dampers 127, are shoved in and all other means of access of air to the oven interior are closed, and the 25 valves 110, and 13, are opened. The fan 15, being set in operation, the gases of distillation are drawn through outlet 109, and forced through scrubbers and condensers 14, 14, to gasometer 16,—valve 18, being open, 30 and valves 20, and 22, being closed. This operation is continued as long as there is a copious flow of gases from the oven 101. When the quantity of gases distilled falls off, or their content of by-products diminishes, the valves 110, 13 and 18, are closed 35 and the valve 20, is opened. The purified gases accumulated in the gasometer 16, then pass through pipe 19, and branches 25, and 33, to gas nozzles 123, and 124, in the doors 40 and side walls of the oven. Air which may or may not be preheated in any well known way is also admitted either through the dampers 127, or air nozzles 107, and 108, or all of these inlets. Cover 103, being removed, the 45 gases introduced into the oven, mixed with those still being distilled off from the charge, burn at a regulated rate, generating all the heat necessary to rapidly complete the coking operation. When the entire charge is 50 coked, the doors are opened, the coke removed, a new charge inserted, and the operation repeated. When batteries of ovens are employed, the initial operations may be assumed as carried on in oven 101, and its 55 fellows, as above described, but when the second, or combustion stage is reached, the first, or distillation stage is also begun in oven 1, and its fellows. The gases so generated in oven 1, may, after purification, be 60 led directly to oven 101, by opening by-pass valve 22, and closing valves 18, and 20. Thus the gases distilled in any one set of ovens during the first, or distillation period, are burned in the other set of ovens, with 65 the residual gases there distilled, during the

second or combustion period therein occurring. The operations alternate. Thus, while one set of ovens are losing heat through distillation of their contents without combustion, the deficiency is largely supplied by the excess heat conducted through the walls from the other set of ovens, sandwiched in between the members of the first set, in which latter set combustion is going on at a rapid rate. Even in this case, however, it is well to run the purified gases through the gasometer; as it serves as a compensating device, absorbing any momentary surplus, and giving it up again when there is a temporary deficit of gas. 70

As a result of the above described operations a charge of a given character and thickness of coal can be completely coked in about half the time that would be required in the old wasting process. This is 75 because the heat is applied in a controllable manner to secure a maximum rate of gas distillation at all times, and in the most efficient way, mainly by combustion in the oven, where the coking process is being carried on. By this method the heat is transmitted directly to the coal also in the oven, or directly to the oven walls and roof, by which the greater portion is later given back 80 again to the next charge, while the lesser portion, which passes through the walls, is not lost, but given over to the ovens on either side, where no combustion is going on. As a further result the by-products are 85 recovered from the richest gases of distillation, only the poorer gases being burned in the oven as evolved. The use of thin flue walls, within which constant combustion must be maintained as in the standard by-product oven, is avoided, and only thick, durable walls are employed, so that the burning out or choking up of elaborate systems of flues is not to be feared. Of course, 90 the process could be carried out with other forms of oven, the gases might be taken from and returned to the oven at points other than those shown in the drawings, and other modifications in detail introduced without departing from the principle of the invention, which comprises drawing off and 95 condensing the richest gases of distillation, without combustion in the oven, during the first period of each coking cycle, and then returning condensed gases to be burned with the final gases of distillation in the oven 100 during the second period of the coking cycle. 105

Having, therefore, described our invention, we claim:

1. The method of coking coal and recovering a portion of the by-products therefrom, comprising the following steps: first, subjecting a body of coal to a partial coking operation by heating it in a closed oven sufficiently to distil therefrom the more volatile gases, under conditions preventing com- 110

bustion; second, extracting by-products from gases so distilled; third, completing the coking of a body of coal partially coked by the above described first step by burning over it and in the same oven gases purified by the above described second step.

2. The method of coking coal and recovering a portion of the by-products therefrom, comprising the following steps: first, subjecting a body of coal to a partial coking operation by heating it in a closed oven sufficiently to distil therefrom the more volatile gases under conditions preventing combustion; second, extracting by-products from gases so distilled and storing said gases; third, completing the coking of a body of coal partially coked by the above described first step by burning over it and in the same oven gases purified and stored by the above described second step.

3. The method of coking coal and recovering a portion of the by-products therefrom, comprising the following steps: first, subjecting a body of coal to a partial coking operation by heating it in a closed oven sufficiently to distil therefrom the more volatile gases under conditions preventing combustion; second, extracting by-products from gases so distilled; third, completing the coking of a body of coal partially coked by the above described first step by burning over it and in the same oven gases purified by the above described second step together with the residual gases distilled from the said body of coal in this final stage of the coking operation.

4. The method of coking coal and recovering a portion of the by-products therefrom which comprises the following steps: first, subjecting the coal in a suitable oven 40 to heat sufficient to distil off the more volatile gases under conditions preventing combustion thereof; second, removing said distilled gases from the oven and extracting the by-products therefrom; third, returning the purified gases to the interior of the oven at a later stage, and burning them, together with the residual gases distilled from the charge, above said charge, until the coking operation is completed.

5. The method of coking coal and recovering a portion of the by-products therefrom, comprising the following steps: first, subjecting a body of coal to a partial coking operation by heating it in a closed oven sufficiently to distil therefrom the more volatile gases under conditions preventing combustion; second, extracting by-products from gases so distilled; third, completing the coking of a body of coal partially coked by the above described first step, by discharging simultaneously into the oven containing it, gases purified by the above described second step and air under pressure and burning in said oven the combustible 60 mixture so formed.
